Primary Examiner — Kevin K Rudzinski

Assistant Examiner — Richard E Yenchesky

(57) CLAIM

The ornamental design for a dustpan and broom set as shown and described.

DESCRIPTION

1. Dustpan and broom set

1.1 : Perspective

1.2 : Front

1.3 : Back

1.4 : Left

1.5 : Right

1.6 : Top

1.7 : Bottom

1.8 : Dustpan and broom separated in a perspective view

The characteristic features of the design lie in the combination of a set of dustpan and broom, that can be fitted into each other; Fig. 1.8 shows dustpan and broom separated.

1 Claim, 8 Drawing Sheets
